UNITED STATES PATENT OFFICE.

CARL P. FRIESE, OF CHICAGO, ILLINOIS.

GRAIN-DRYING APPARATUS.

No. 797,351.

Specification of Letters Patent.

Patented Aug. 15, 1905.

Application filed November 12, 1904. Serial No. 232,442.

To all whom it may concern:

Be it known that I, CARL P. FRIESE, a citizen of the United States, residing at Chicago, in the county of Cook and State of Illinois, have invented new and useful Improvements in Grain-Drying Apparatus, of which the following is a specification.

This invention relates to improvements in a grain-drying apparatus, and has for its object to provide a device of this class that is simple in construction, is easily operated, and presents a large area of heating drying surface within a compact space.

This apparatus is more especially intended to be of the portable type, so that the same can be conveniently moved from place to place as the work may require. It is, however, obvious that it may be constructed of large proportions in a stationary position where large quantities of different kinds of grain are handled in bulk.

In the drawings, Figure 1 is an elevation of an apparatus embodying the improved features. Fig. 2 is a longitudinal section on line 2, Fig. 1, looking in the direction indicated by the arrow; and Fig. 3 is a transverse section on line 3, Fig. 1.

A represents a hollow cylinder which is rotatably mounted on a supporting frame or base B. The companion sheaves 4 and 5 are rigidly mounted on the cylinder and are located adjacent to the respective ends thereof. But two mounting-sheaves are shown in illustrating a practical working device. It will be understood, however, that this number may be increased in accordance with the length, diameter, and weight of the cylinder to be supported.

A number of friction-rollers 6 are provided with suitable journal-bearings in the frame and are relatively located in engagement with the sheaves 4 and 5, as best shown in Figs. 2 and 3, in supporting the cylinder A in its revoluble position. A driving gear-wheel 7 is also mounted on the cylinder A and illustrates one means for receiving motion from the motive power to be utilized.

A hollow drier-body C is located inside of the cylinder A and extends longitudinally therewith, as best shown in Fig. 2. The body C is triangular in cross-section and presents inclined surfaces 8 and 9, providing a large area of heating-surface within a compact space. A series of distributing buckets or carriers 10 are rigidly, Figs. 2 and 3, to the inner circumferential surface of the cyl-

der A and serves the purpose of carrying the grain upward and discharging or dropping the same onto the inclined drying-surface presented by the drier-body C.

The cylinder A is provided in the discharge end with an opening 11, the diameter of which is reduced by an inturned flange 12, which checks too rapid an outflow of the grain. This end of the cylinder is loosely covered by a cap 13, supported in a stationary position by one or more brackets 14. This cap is provided with a spout 15, through which the grain is discharged in the operation of drying. The intake end of the cylinder is provided with a receiving-hopper 16 opening therein.

A heat-generating furnace 17 has a heat-conducting pipe 18 connecting therewith, which leads through and heats the drying-surface of the triangular body C and then ends in a suitable escape-flue. Another form of heating apparatus from that shown may be used. Steam heat may be used when convenient.

The cylinder A is set on an incline, so that the grain being treated will gradually gravitate to the point of discharge with each revolution. The degree of inclination and the speed of rotation may be varied in accordance with the condition of the grain and the length of time it must be retained in the cylinder in completing the process of drying.

In operation the grain to be dried is gradually fed through the hopper end of the cylinder and is picked up by the series of buckets and carried upward with each revolution and distributed over the inclined surfaces of the drier-body, from which the grain gravitates back to the lower part of the cylinder to be again carried up, and so on in continuous order of circulation until it gradually escapes from the discharge end in a dried condition.

Having thus described my invention, what I claim is—

1. In a grain-drying apparatus, a hollow cylinder rotatably mounted in an inclined position, a stationary drier-body triangular in cross-section and extending longitudinally through said cylinder, and a heating-pipe extending through said drier-body and projecting from both ends of said cylinder.

2. In a grain-drying apparatus, a revoluble cylinder, a number of carrier-buckets disposed at intervals around the inner circumferential surface of said cylinder and set at an oblique angle with reference to the axis there-

of, a hollow stationary drier-body triangular in cross-section and inclosed within said cylinder, a heating - pipe extending longitudinally through the drier-body and projecting from the respective ends of said cylinder, and means for supporting said cylinder in a rotatable position.

In testimony whereof I have signed my name to this specification in the presence of two subscribing witnesses.

CARL P. FRIESE.
